PROPELLING MECHANISM FOR TRACTION OPERATED MACHINES

Filed Oct. 1, 1927

UNITED STATES PATENT OFFICE

BERLIN S. FERGUSON, OF MARION, OHIO, ASSIGNOR TO THE MARION STEAM SHOVEL COMPANY, OF MARION, OHIO, A CORPORATION OF OHIO

PROPELLING MECHANISM FOR TRACTION OPERATED MACHINES

Application filed October 1, 1927. Serial No. 223,415.

This invention relates to propelling mechanism for traction operated machines and more particularly to a mechanism for propelling and steering excavating machines and the like which are mounted on crawling traction trucks.

One object of the invention is to provide a machine of this kind in which trucks on the opposite sides of the machine will be separately propelled and may be driven at the same speed or at different speeds.

A further object of the invention is to provide a machine of this kind with improved mechanism for manipulating the trucks to steer the machine.

A further object of the invention is to provide such a machine in which the trucks at one end of the machine may be separately driven and in which steering movement may be imparted to both trucks from the driving mechanism for either truck.

A further object of the invention is to provide such a machine having means for turning the trucks to steer the machine and in which the trucks having the greatest distance of travel during the turning of the machine may be driven at higher speed than the other trucks.

A further object of the invention is to provide a propelling and steering mechanism of this kind which will be simple in its construction and operation and which may be easily manipulated to cause the machine to travel in the desired direction.

Other objects of the invention will appear as the mechanism is described in detail.

The accompanying drawing is a plan view of a propelling and steering mechanism embodying my invention, showing a portion of the main frame.

In this drawing I have illustrated one embodiment of the invention and it will be understood that this particular embodiment has been chosen for the purpose of illustration only and that the several parts thereof may take various forms and may be arranged in various ways without departing from the spirit of the invention.

As here illustrated the mechanism comprises four trucks arranged in pairs at the

front and rear ends, respectively, of a main frame or base 1, a portion only of which is shown. It will be understood that the several trucks are arranged at the respective corners of the main frame, and thus provide the sole support for that frame. In power shovels, or other excavating machines, of the revolving type a platform is rotatably mounted upon the main frame 1 and this platform carries the excavating machinery and power plant but inasmuch as the revolving platform and the mechanism carried thereby form no part of the present invention they have not been illustrated. The power plant on the revolving platform is connected with the propelling mechanism for the trucks by means of a vertical shaft 2 extending through the platform and the main frame at the axis of the platform, in the usual manner. In the present arrangement this vertical shaft is connected at its lower end, by means of beveled gears 3, with a short shaft 4 extending lengthwise of the main frame and journaled in bearings 5 carried by that frame.

The driving mechanism by means of which the several trucks are propelled may take various forms but preferably this driving mechanism is of such a character that the trucks on one side of the machine may be driven independently of the trucks on the other side of the machine, thus enabling the trucks on the two sides of the machine to be operated in unison or at different speeds, or enabling the trucks on one side of the frame to be operated while the trucks on the other side of the frame remain idle. In the present construction the trucks on each side of the machine are driven in unison. The trucks themselves may be of any suitable character but I have here shown them as the crawling traction type. Each truck comprises a truck frame 6 mounted for movement about a vertical axis 7 and having on each side thereof an endless track or crawling traction device 8. Each truck frame has a longitudinally extending steering arm 9 by means of which the truck may be turned about its vertical axis. Each truck is provided with a transverse shaft 10 having its inner portion journaled in bearings 11 on the

main frame and having its outer portion 12 mounted in the truck frame and connected with the inner portion by universal joints 13, thus permitting the shaft to accommodate itself to varying positions of the truck with relation to the main frame. The outer portion 12 of the shaft is connected with the crawling traction devices or endless tracks 8 by suitable connecting mechanism, such as gear trains, but inasmuch as this connecting mechanism forms no part of the present invention it has not been illustrated. The inner portion of each shaft 10 has secured thereto a beveled gear 14 which meshes with a beveled pinion 15 on a longitudinally extending shaft. In the present instance there are two of these longitudinal shafts, as shown at 16 and 17, the shaft 16 being connected with the shafts 10 on one side of the machine and the shaft 17 being connected with the shafts 10 on the other side of the machine. The longitudinal shafts may be connected with the vertical shaft in any suitable manner but I prefer to interpose variable speed mechanism between the respective longitudinal shafts and said vertical shaft. As here shown, I have loosely mounted on the respective longitudinal shafts 16 and 17 high speed gears 18 and 19 and low speed gears 20 and 21. The high speed gears of the two shafts both mesh with a pinion 22 on the shaft 4, which is connected with the vertical shaft, and the low speed gears 20 and 21 both mesh with a pinion 23 on the shaft 4. The two shafts have mounted thereon clutches 24 and 25 adapted to connect either the high speed gears or the low speed gears with the respective shafts or to disconnect both of said gears from the respective shafts. Thus the two longitudinal shafts may be driven in unison at the same speed, or they may be driven simultaneously at different speeds, or one shaft may be driven and the other may remain idle.

The steering mechanism by means of which the several trucks are turned about their vertical axes may take various forms but preferably it is of such a character that the trucks at one end of the machine may be turned independently of the trucks at the other end of the machine, thus enabling the respective pairs of trucks, at the opposite ends of the machine, to be turned either in the same direction or in opposite directions.

In the present installation I have provided each pair of trucks with rotatable steering member or shaft which extends transversely to the main frame and is here shown as comprising an intermediate portion 26 journaled in bearings 27 on the main frame, and outer or end portions 28 which are connected with the intermediate portion by universal joints 29 and which have their outer ends screw threaded, as shown at 30, and extending 65 through nuts 31 carried by the steering arms

9 of the respective trucks. The nuts 31 are preferably rotatable about longitudinal axes with relation to the respective steering arms to permit the same to accommodate themselves to varying positions of the truck with relation to the main frame. Mounted on the intermediate portion 26 of the steering member are beveled gears 32 which mesh with pinions 33 on short shafts 34 journaled in bearings 35 on the main frame and each having at its other end a spur gear 36 which meshes with a spur pinion 37 loosely mounted on the adjacent longitudinal shaft, 16 or 17. Clutches 38 and 39 are mounted on shafts 16 and 17, respectively, to control the connection of the steering mechanism therewith and, in the present instance, these clutches are independently operable, thus enabling the steering mechanism for either pair of trucks to be connected with either of the longitudinal shafts of the propelling mechanism.

The several clutches for the propelling and steering mechanisms may be operated in any suitable manner but it will be understood that machines of this type are seldom propelled any great distance under their own power but that the propelling and steering thereof is for the most part for the purpose of shifting the machine with relation to the work and, further, that the machine moves slowly from one position to the other. Consequently the clutches are not frequently operated and it is entirely practical for these clutches to be shifted by a man on the ground and not by the operator on the machine. Therefore, it is not essential that there should be any means mounted on the platform for manipulating these clutches. I have therefore shown no operating mechanism therefor.

When the machine is to be propelled straight ahead the clutches 25 and 24 are manipulated to connect either the high speed gears 18 and 19 or the low speed gears 20 and 21 with the longitudinal shafts 16 and 17, thus causing the trucks on both sides of the machine to be propelled at the same speed. When a turn is to be made the clutch 38 or 39 at the front end of the machine and on that side toward which the turn is to be made is manipulated to connect the steering mechanism for the front trucks with one of the longitudinal shafts. The propelling clutches 24 and 25 are manipulated to connect that longitudinal shaft which is connected with the steering mechanism with the low speed gear, 18 or 19, and to connect the other of said longitudinal shafts with the high speed gear, 20 or 21, thus causing trucks on the outer side of the machine to travel at a greater speed than the trucks on the inner side of the machine, thereby compensating for the difference in distance which must be traveled by these trucks. Assuming that the

machine is traveling in the direction of the arrow and it is desired to turn to the right as shown in the drawing, or to the left with relation to the travel of the machine, the 5 clutch 24 is thrown into mesh with the low speed gear 20 on the shaft 16 and the clutch 25 is thrown into mesh with a high speed gear 19 on the shaft 17. The clutch 38 is then thrown into mesh with the pinion 37 to 10 connect the steering mechanism with the shaft 16, thus causing the front trucks to be turned in the desired direction and causing the inner trucks to be driven at a lower speed than the outer trucks. If a shorter turn is 15 desired the clutch 39 at the rear end of the shaft 17 may be thrown into mesh with its pinion 37 to cause the rear trucks to be turned in a direction opposite to the direction in which the front trucks are turned. When 20 the trucks have been turned to the desired extent the clutches 38 and 39 are disconnected and the machine propelled by the shafts 16 and 17 until the turn has been completed. The clutch 39 at the front end of the machine 25 and the clutch 38 at the rear end of the machine are then thrown in to restore the several trucks to their normal or straight line positions, after which the steering clutches are all disconnected and the clutch 25 shifted 30 to connect the shaft 17 with the low speed gear 21, thus causing the machine to be moved straight ahead at a low speed. If it is desired to shift the machine laterally without changing the longitudinal position of 35 the main frame this may be accomplished by connecting both clutches 24 and 25 with the low speed gears 20 and 21, then connecting the shaft 16 or 17, according to the direction in which the frame is to be moved, with the 40 steering mechanism for both the front trucks and the rear trucks, thereby causing both of these trucks to be turned in the same direction so that the line of travel will be oblique to the length of the frame. While 45 I have treated the lower end of the machine, in the drawings, as the front end, it will be obvious that the machine may be driven in either direction by reversing the direction of rotation of the vertical shaft and that the 50 controlling mechanism will operate in the same manner as described when the machine moves in either direction.

While I have shown and described one embodiment of my invention I wish it to be 55 understood that I do not desire to be limited to the details thereof as various modifications may occur to a person skilled in the art.

Having now fully described my invention, what I claim as new and desire to secure by 60 Letters Patent, is:

1. In a mechanism of the character described, a pair of trucks each mounted for movement about a vertical axis, separate driving mechanisms for propelling the respective trucks, steering mechanism common to

both trucks to move the same simultaneously about their vertical axes, and means for connecting said steering mechanism with either of said driving mechanisms.

2. In a mechanism of the character described, a pair of trucks each mounted for movement about a vertical axis, separate driving mechanisms for propelling the respective trucks, each driving mechanism comprising a variable speed device, and means for connecting the same with a common source of power, steering mechanism common to both trucks to move the same simultaneously about their vertical axes, and means for connecting said steering mechanism with either of said driving mechanisms. 70

3. In a mechanism of the character described, a pair of trucks, separate mechanisms for propelling the respective trucks, each comprising a transverse shaft connected with one of said trucks and a longitudinal shaft having operative connection with said transverse shaft, variable speed devices for connecting the respective longitudinal shafts with a common source of power, mechanism for imparting steering movement to said trucks, and means for connecting said steering mechanism with either of said longitudinal shafts. 80

4. In a mechanism of the character described, a pair of trucks, separate mechanisms for propelling the respective trucks, each comprising a shaft and means for connecting the same with one of said trucks, a rotatable steering member connected with both of said trucks, separate gear trains to connect said rotatable member with the respective shafts, and clutches to control said connections. 95

5. In a mechanism of the character described, a pair of trucks, separate mechanisms for propelling the respective trucks, each comprising a shaft and means for connecting the same with one of said trucks, a rotatable steering member connected with both of said trucks, means actuated by one of said shafts 100 to rotate said steering member in one direction, means actuated by the other shaft to rotate said steering member in the other direction, and means for separately connecting said rotating means with the respective shafts. 110

6. In a mechanism of the character described, a pair of trucks, separate driving mechanisms for propelling the respective trucks, each mechanism comprising a shaft 115 and means for operatively connecting the same with one of said trucks, two gears of different diameters loosely mounted on each shaft, pinions meshing with the corresponding gears on the two shafts, means for actuating said pinions, a clutch on each shaft to separately connect said gears therewith, a device connected with both trucks to impart steering movement thereto, separate gear trains to connect said steering device with the 120

125

130

- respective shafts, and clutches to control said connections.
7. In a mechanism of the character described, a pair of trucks each movable about a vertical axis and each having a steering arm, separate driving mechanisms for propelling the respective trucks, a rotatable steering device comprising an intermediate portion and end portions having universal connection with said intermediate portion, said end portions having screw threaded connection with the respective steering arms, and means for detachably connecting said intermediate portion with either of said driving mechanisms.
- 15 8. In a mechanism of the character described, two pairs of trucks, each truck being mounted for movement about a vertical axis, driving mechanism for propelling said trucks comprising two shafts, means for operatively connecting each shaft with the corresponding trucks of the two pairs of trucks, means for rotating said shafts, rotatable steering members operatively connected with the two trucks of the respective pairs of trucks, and 20 clutch controlled means for operatively connecting said steering members with either of said shafts.
- 25 9. In a mechanism of the character described, two pairs of trucks, each truck being mounted for movement about a vertical axis, driving mechanism for propelling said trucks comprising two shafts, means for operatively connecting each shaft with the corresponding trucks of the two pairs of trucks, means for 30 rotating said shafts at the same speed or at different speeds, rotatable steering members extending transversely to said shafts near the opposite ends thereof and each operatively connected with both trucks of the adjacent 35 pair of trucks, separate gear trains for connecting each steering member with the respective shafts, and means for establishing and interrupting the connection between said gear trains and said shafts.
- 40 10. In a mechanism of the character described, a pair of crawling traction trucks each mounted for movement about an individual vertical axis, driving mechanism for separately propelling said trucks simultaneously at different speeds, means for connecting said driving mechanism with a source of power, steering mechanism for turning said trucks about said vertical axes, and means for operatively connecting said steering mechanism with said driving mechanism.
- 45 11. In a mechanism of the character described, a frame, a pair of crawling traction trucks mounted at opposite sides of said frame and each movable about an individual vertical axis, a member connected with both trucks of said pair to move the same in unison about their vertical axes, separate driving mechanisms for propelling said trucks, means for separately controlling the operation of 50 said driving mechanisms, and means for sep- 55 arately connecting said driving mechanisms with said member.
12. In a mechanism of the character described, two pairs of trucks each being movable about an individual vertical axis, driving mechanism for simultaneously propelling all of said trucks and for simultaneously propelling the two trucks of each pair at different speeds, steering mechanism for separately operating the respective pairs of trucks to turn the same about their vertical axes, and selective means for operatively connecting said steering mechanism with said driving mechanism.
- 60 In testimony whereof, I affix my signature hereto.
